WITNESS:

UNITED STATES PATENT OFFICE.

EDWARD HAUSER, OF NEW YORK, N. Y.

HOSE SUPPORTER.

Application filed December 27, 1926. Serial No. 157,356.

This invention relates to improvements in hose supporters and more particularly to ladies' garters.

The primary object of the invention is to provide a hose supporter in which the garter strain upon the hose is greatly eased during certain natural positions, of a wearer such as while walking and bending, thereby preventing runs in the hose or stocking.

10 Another object of the invention is to provide a lady's garter which will not become taut when a strain is applied thereto, i. e., the elastic from which the garter is constructed will never reach its full stretching point, as extra 15 play is provided for receiving the excess strains at all times.

A further object of the invention resides in a lady's garter so constructed and designed as to receive its main support from a point at the 20 hips of the wearer, thereby eliminating the bulging at the waist lines caused by the pull at the front of the girdle, or waist encircling band, which band or girdle forms part of a lady's wearing apparel and from which the 25 garters are suspended.

A further object of the invention is the provision of a lady's hose supporter which is neat in appearance, comfortable when worn, and simple and inexpensive of manufacture.

30 With these and other objects in view, the invention resides in certain novel construction and combination and arrangement of parts, the essential features of which are hereinafter fully described, are particularly pointed out 35 in the appended claim, and are illustrated in the accompanying drawing, in which:—

Figure 1 is a perspective view of the preferred form of my hose supporter in position upon a wearer.

40 Figure 2 is a perspective view of the same per se and looking toward the rear thereof.

Figure 3 is a perspective view of a modified form of my invention.

Referring more particularly to the drawings, the reference numeral 10 designates a 45 waist encircling band in the form of a girdle, corset or belt, which is shown as buttonable in the front as at 11.

In the preferred form of my invention 50 shown in Figures 1 and 2 of the drawings, the waist encircling band is shown as a girdle having a fabric front 12, to the lower edge of which eyes or loops 13 and 14 are fixedly attached and which depend therefrom on opposite sides of the buttonable front 11. The garter is constructed of a single length of elastic

webbing 15 and has one of its ends extending through the eye or loop 13, and its free end provided with an adjustable buckle 16, through which the vertical lead 17 of the webbing extends. The webbing extends through an eye or loop 18 of a hose supporting clasp 19, and then passes upward at an angle with respect to the vertical lead over the upper part of the hip or thigh portion of the girdle from 65 where it passes through loops 20 disposed at opposite sides of the girdle at the back thereof, and a central loop 21 also at the rear, but which loop 21 extends approximately the height of the girdle. After passing through the loops 70 20 and 21, the strip of elastic webbing is brought downward at the opposite side of the girdle through an eye 22 of a hose engaging clasp 23, and thence upward through the loop 14 to provide a second vertical lead 24 adapted 75 to lie against the other leg of the wearer. The other end of the webbing is attached to an adjusting buckle 25 similar to the buckle 16 for varying the length of the vertical lead 24.

From the foregoing, it will be seen that the 80 elastic webbing is freely slidable through the loops 20 and 21 and through the loops 18 and 22 of the hose clasps and which webbing may be of an elastic fabric having a smooth facing such as silk or satin, if desired. 85

When the clasps 19 and 23 are fastened to the top of the stocking as shown in Figure 1 of the drawings, and the wearer is standing in an erect position, it will be seen that the strain or pull is evenly divided on the elastic webbing, as the webbing encircles the back of the wearer and rests upon the narrow part of the hips, which supports most of the strain. Should more strain be placed on one of the supporters than on the other, such as when 95 a person is stooping with one leg bent, the webbing will freely slide around the waist and compensate for its excessive strain. It will be noted that a pull on either of the supporters will take up any slack in the length of the 100 elastic webbing before the stretching of the same takes place.

In Figure 3 of the drawings, I have shown a slightly modified form of my invention wherein the elastic webbing extends across the 105 front of the girdle 10 through loops or eyes 26 attached to the sides thereof. In this form, the supporter is constructed of two separate strips of elastic webbing A and B, one of the ends of each being supported from the 110 lower front edge of the girdle as shown and described in the preferred form, while the

free ends pass through the respective eyes 26 and are detachably connected together by a buckle 27 disposed to one side of the buttonable front 11 of the girdle by suspending 5 the supporters from the front of the girdle, the same serving to give added support to the abdomen of the wearer.

From the foregoing, it will be seen that the different forms of my invention include the 10 same principle, i. e., the provision of a means for relieving any excess strain on any one hose supporter, by providing hose clasp suspenders which are slidably supported from the girdle, corset or belt of the wearer.

15 While I have described what I deem to be the most desirable embodiment of my invention, it is obvious that many of the details may be varied without in any way departing from the spirit of my invention, and I therefore 20 do not limit myself to the exact details of construction herein set forth nor to anything less

than the whole of my invention limited only by the appended claim.

What is claimed as new is:—

A lady's hose supporter comprising a waist 25 encircling band, guide loops at the sides and back of said waist encircling band, the back loop being disposed on a plane higher than the side loops, a single length of elastic webbing 30 passing through said loops and slidably supported thereby, so that the elastic webbing passes about the top of the back and lower sides of the waist encircling band, said webbing having its free ends fixedly connected to the lower front edge of the waist encircling 35 band, and garter clasps slidable on said elastic webbing substantially as and for the purposes specified.

In testimony whereof I have affixed my signature.

EDWARD HAUSER.
